FIG. 1

FIG. 2

FIG.3

FIG.4

FIGURE 1 is a perspective view of a lighting fixture showing my new design.

FIGURE 2 is a rear view of the lighting fixture of FIGURE 1.

The support bracket in FIGURE 2 is shown broken away for convenience of illustration.

FIGURE 3 is a side elevational view of one side of the lighting fixture of FIGURE 1.

FIGURE 4 is a side elevational view of the other side of the lighting fixture of FIGURE 1.

The characteristic features of my design reside in the specific configuration of the lamp fixture base in combination with the support bracket as shown.

I claim:

The ornamental design for a lighting fixture, as shown and described.
